UNITED STATES PATENT OFFICE.

FORREST G. PURINTON, OF WATERBURY, CONNECTICUT.

ELECTROPLATING APPARATUS.

Application filed October 25, 1922. Serial No. 596,788.

To all whom it may concern:

Be it known that I, FORREST G. PURINTON, a citizen of the United States, and a resident of Waterbury, county of New Haven, and 5 State of Connecticut, have invented certain new and useful Improvements in Electroplating Apparatus, of which the following is a specification.

This invention relates to electroplating 10 and more particularly to a mechanically operated electroplating apparatus designed to plate large quantities of small articles in bulk.

One object of this invention is to provide 15 an electroplating apparatus having a rotary plating barrel which may be easily and quickly raised and lowered from the plating tank for draining, dumping, and recharging without the use of cranes, over-head 20 trolleys or other complicated mechanism.

A further object is to provide an electro- 25 plating apparatus in which the operation of raising the tumbling barrel out of the plating tank will automatically shut off the current and at the same time disconnect the driving mechanism.

A further object is to provide improved 30 anode and cathode connections for the plating barrel and tank.

A further object is to provide resilient 35 cathode brushes adapted to engage the shaft of the rotary plating barrel when the latter is in plating position.

A further object is to provide a rotary 40 plating barrel having an improved form of dumping door and improved means for detachably locking said door to said barrel.

A further object is to provide an electro- 45 plating tank having a series of anodes of improved form and shape, said anodes being secured to the current lead wires by an im- 50 proved method.

A further object is to provide an electro- 55 plating apparatus of the above nature having an improved form of guiding pan associated with said plating barrel, said pan being adapted when in the draining position to direct the dripping electrolyte back into the plating tank, and when in dumping position to serve as a chute to direct the plated articles into a suitable receptacle.

A further object is to provide an apparatus 60 for electroplating a mass of small articles which will be simple, cheap to man- 65 ufacture, easy to operate and very efficient and durable in use.

With these and other objects in view, there have been illustrated on the accompanying drawings one form in which the invention may be conveniently embodied in practice. 60

Fig. 1 represents a front perspective view of the complete electroplating apparatus with the parts arranged in plating position.

Fig. 2 is a rear perspective view of the 65 same.

Fig. 3 is a top view of the plating tank and rotary plating barrel, with certain parts removed for greater clearness—the plating barrel being shown in section.

Fig. 4 is a front view of the apparatus 70 with certain parts broken away and with other parts removed for greater clearness.

Fig. 5 is a front perspective view of the apparatus with the plating barrel shown in 75 dumping and recharging position.

Fig. 6 is a perspective view of the guiding pan, showing the manner in which it is connected to the fulcrum shaft.

Fig. 7 is a perspective view of one of the 80 cathode brushes and a portion of its current lead wire.

Fig. 8 is a perspective view of the plating 85 tank and anodes, certain parts being broken away, and other parts being removed for greater clearness.

Fig. 9 is a perspective view of the plating barrel, shown detached from the remainder of the apparatus and with its cover removed.

Fig. 10 is a perspective view of the detachable cover of the plating barrel. 90

Fig. 11 is a sectional view taken through 95 the edge of the barrel and its detachable cover, showing the method by which these parts are fastened together.

Fig. 12 is a sectional view taken through 100 the upper end of one of the anodes, showing the manner in which the current lead wire is swaged thereto.

Referring now to the drawings in which like reference numerals denote corresponding parts throughout the several views, the numerals 10 and 11 represent side standards or supports for the semicircular plating tank 12. The plating tank 12 is preferably constructed of wood and has heads 13 and 14 105 fitted within annular grooves 15 formed near the sides of the circular rim 16 of the plating tank. As will be clear from the drawing, the heads 13 and 14 of the tank 12 are not flush with the ends of the circular rim 16 but are spaced inwardly a short distance therefrom. The semicircular rim 16 is made 110

up of a series of parallel longitudinal strips constituting part of the framework of the tank. Stay-rods 18 which pass through the ends of said enlarged strips are employed 5 for connecting the top portions of the frames 10 and 11. The rods 18 are threaded at their ends and may be readily tightened by screwing the nuts 18^a against the washers 18^b located thereon.

10 The semi-circular rim 16 of the tank 12 is also braced by means of a series of curved semi-circular rods 19, (three in this instance,) which are threaded at their ends and provide with nuts 20 and washers 20^a 15 seated within suitable recesses 21 which are open at the top and on the sides to permit easy manipulation by a wrench or other tool. The rim of the tank is slotted at each end, the slotted portions embracing bars 22 and 23 of the side frames 10 and 11, whereby the tank is firmly supported 20 against longitudinal movement. The side bars 22 and 23 are preferably secured to base strips 23^a of the standards 10 and 11 25 by means of bolts 23^b and 23^c as clearly shown in Fig. 4.

A series of anodes 24 of any suitable number are directly supported in the plating tank upon longitudinal strips 24^a. The 30 anodes 24 are preferably made semi-circular to correspond with the shape of the rim of the plating tank 12, and it will be noted that no hooks are required to support them as was the case in former types 35 of apparatus.

The anodes 24 are preferably rectangular in cross section, but it will be understood that circular or elliptical anodes may be employed if desired.

40 The terminals of the anodes 24 may be connected to current lead wires 26 in any suitable manner, but it is preferred to insert the ends of the lead wires 26 in drilled holes 25 in the anode terminals (Fig. 11) 45 and then to swage up the metal of the anodes at 27 to form tight electrical connections. The lead wires 26 may be connected to a suitable bus bar (not shown) or other suitable source of current.

50 The heads 13 and 14 of the plating tank are provided with circular recesses 28 which are adapted to provide clearance for a shaft 29 having a rotary tumbling barrel 30 fixedly mounted thereon. A fulcrum shaft 31 is 55 mounted in fixed bearings 32 and 33 located near the sides of the tank heads 13 and 14. The fulcrum shaft 31 preferably extends out on each end slightly beyond the bearings 32 and 33 as clearly shown in 60 Figs. 1 and 5, and said extending ends are provided with barrel operating arms 34 and 35. The barrel operating arms 34 and 35, and the fulcrum shaft 31 thus constitute a rigid frame adapted to rock about its axis 65 to move the tumbling barrel into plating,

draining, and dumping position, as may be desired. The fulcrum shaft 31 is also provided—beyond the barrel operating arm 35—with a gear 96 for rotating the barrel, as will be hereinafter more fully described. 70

The barrel operating arm 34 is provided with an extension 36, said extension 36 being provided with a pair of ears 37, and being adapted to lie in a recess 37^a in a disk-shaped counterweight 38. The counterweight 38 is secured to the arm 36 by the use of a bolt 39 having a head 40 on one end and a washer 41 and nut 42 on its other end. In the present embodiment of the invention, only a single counterweight 80 disk has been disclosed, but it will be understood that extra disks or "wafers" may be added if desired, whenever the weight of the material being plated becomes excessive. 85

As most clearly shown in Figs. 3, 4, and 9, the barrel 30 consists of a pair of heads 43 and 44, which are preferably polygonal in shape, having in this instance sixteen sides. Each of the heads 43 and 44 is split into two halves, and is provided with a central shaft-hole 45 surrounded by four symmetrically spaced apertures 46 for receiving the cathode wires. An aperture 47 is also provided for receiving a dowel pin 48 for the purpose of locking a barrel cover 49 to the barrel 30. 90

The barrel heads 43 and 44 are connected on their flat edges by means of a series of flat perforated strips 50, preferably of wood, said strips being secured in position by any suitable non-metallic means, such as wooden pegs 51 (Fig. 11). Mounted on each barrel head are a pair of parallel wooden cleats 52 for connecting the halves of said barrel head, said cleats having holes 52^a in alignment with the apertures 46 to permit the passage of cathode rods 61, four in number in this instance. 100

The barrel cover 49 preferably consists of a pair of heads 53 and 54 formed substantially in the shape of a segment of a circle of the same diameter as the barrel heads, and having on its circumference a series of flat sides corresponding with the sides of the polygonal heads 43 and 44 of the barrel. The cover heads 53 and 54 are connected by means of cross staves 55 similar in all respects to the strips 50 of the barrel. The barrel heads are provided with apertures 56 having flanged bushings 57 seated thereon. A similar flanged bushing 58 is seated in each of the apertures 47 of the barrel heads previously described. The bushings 57 and 58 may be made of any suitable non-conducting material such as rubber, porcelain, or the like. 110

The dowel pin 48 (Fig. 11) is provided with a shoulder 59 adapted to engage a flange 59^a on the bushing 57 of the cover 120 125 130

head. The dowel pin 48 may also be provided with a knob 60 to facilitate the convenient manual manipulation thereof. Moreover, if desired, rubber tubing (not shown) may be employed on the edges of the cover where it comes into contact with the barrel to form a tight joint.

The cathode of the electroplating apparatus is located within the barrel 30, and 10 comprises a series of spaced metal rods 61, four in this instance. These metal rods 61, as more clearly shown in Fig. 3, extend the entire length of the barrel 30, and pass through the apertures 46 and 52^a in 15 the heads 43 and 44 beyond which the rods 61 are bent inwardly at right angles radially toward the shaft 29. The metal cathode rods 61 are preferably equally spaced around the circumference of the barrel 30 so that at least one of them will 20 always be immersed in the plating solution and in contact with the mass of metal articles being plated. The terminals 61^a of said cathode rods 61 are flattened and 25 perforated so that they may be connected in any suitable manner, as by bolts 62, to the flanges 63. The flanges 63 are rigidly secured to the shaft 29, as by the pins 64. The terminals 61^a of the cathode rods 61, 30 as well as the angular sections which pass through the apertures 46 and 52^a are preferably protected by short lengths of rubber tubing 65, shown partly broken away in 35 Fig. 4, which serve to insulate the sections of the cathodes not intended to contact with work to be plated, and thereby prevent any current leakage or stray current. The flanges 63 and their cathode connections are 40 preferably insulated from the solution by means of asphaltum paint or other suitable material.

After passing out of the plating solution through the cathode rods 61 and the flanges 63 at the ends of the barrel, the plating 45 current is conducted through both ends of the shaft 29 to a pair of resilient brushes 66, whence it leaves the apparatus through a suitable conducting wire 72^a leading to a bus bar, not shown.

50 Each of the brushes 66 as shown in Fig. 7 is provided with a flat base 67 having a pair of apertures 68 and 69. A screw bolt 70 is adapted to fit within the aperture 68 to secure the brush to the heads 13 and 55 14 of the tank. The other apertures 69 are provided with bolts 71 having nuts 72 threaded thereon for tightly holding the flattened and perforated ends of the conducting wires 72^a. Each of the brushes 66 has 60 an upstanding intermediate section 73 terminating in a cylindrical top portion 74, said top portion being split into a plurality of downwardly extending resilient fingers 75 adapted to engage the shaft 29 when the 65 barrel is in plating position. One advan-

tage of the split construction of the brushes 66 is that the current passes from the shaft 29 through a large number of paths and the contact surfaces are always kept clean. While in the preferred embodiment of the invention herein illustrated, brushes 66 are mounted upon both ends of the electroplating tank, as shown, it will be understood that it is within the spirit of the present invention to employ only a single brush if 70 desired.

In order to permit the plating barrel to readily drain into the tank, and also to direct the plated articles into a suitable receptacle 99, provision is made of a guiding pan rigidly mounted on the fulcrum shaft 31. As most clearly shown in Fig. 6, the guiding pan comprises a flat base 76 having a pair of securing straps 77 secured thereto as by rivets 78. The straps 77 are looped at 79, near one end, away from the flat base 76, said looped sections being fitted about the fulcrum shaft 31 and adjustably secured thereto at any desired angle by means of the screw bolts 80. The sides of the guiding pan are preferably bent upwardly at right angles from the base 76 and have parallel sections 81 and converging sections 82.

The mechanism for rotating the barrel for tumbling the work is operated only when the latter is in plating position and comprises a pulley 83 continuously driven by a belt 84. The pulley 83 is keyed to a shaft 85 rotatably mounted in a bearing 86 secured to the tank head 13 in any suitable manner as by screws. A gear 87 is secured to the pulley shaft and is adapted to automatically come into mesh with a gear 88, fastened upon the end of the barrel shaft 29, when the barrel 30 is lowered to plating position.

The mechanism for manually rocking the barrel out of the tank into draining and dumping positions, when the plating has 100 been completed, comprises a worm shaft 89 mounted in a bearing plate 90, the latter having enlarged journal portions 91 and 92. A hand wheel 93 having a suitable handle 94 is secured upon the outer end of the worm shaft 89.

When the hand wheel 93 is operated, a worm 95 on the shaft 89 and a gear 96 meshing therewith will be rotated. The gear 96 is fixedly secured to the end of the fulcrum shaft 31 beyond the point of attachment of the arm 35 and its rotation will rock the barrel 30 about the fulcrum shaft 31. One advantage of this construction is that a small force exerted upon the handle 94 will be sufficient to cause the plating barrel—together with a heavy charge of metallic articles—to be easily rocked about its axis into and out of the plating tank.

It will also be noted that by reason of the friction between the worm 95 and the gear 125

96 the mechanism will be self-locking, and the barrel will remain in any desired position without additional supporting means.

In order to limit the downward rocking movement of the barrel in its plating and dumping positions respectively, a pair of upstanding stops 97 and 98 are provided upon the outer and inner ends respectively of the worm shaft bearing 90. A similar pair of stops 97^a and 98^a may also be located on a bracket 98^b. The stops 97 and 97^a are preferably made adjustable to permit the gears 87 and 88 to accurately mesh.

In operation, assuming that the plating 15 of one batch of articles has been completed, the barrel may be raised out of the plating solution into draining position by rotating the handwheel 93 in clockwise direction. The guiding pan will then direct the dripping liquid back into the tank. The operation 20 of raising the barrel out of its normal plating position will move the shaft 29 out of contact with the brushes 66 and the electrical circuit through the plating tank will thus be automatically broken. At the same 25 time, the barrel-tumbling gear 88 mounted on the shaft 29 will automatically cease to revolve, as it will move out of mesh with the driving gear 87.

30. After the barrel has drained sufficiently, the operator will continue the rotation of the handwheel 93 until the barrel has been moved to the dumping and recharging position shown in Fig. 5. The dowel pins 48 may 35 then be taken out by manipulating the knobs 60, whereupon the cover 49 may be removed from the barrel 30. The barrel may then be readily dumped into a suitable receptacle 99 by rotating it about the shaft 29 until the 40 uncovered opening is immediately above the guiding pan, the inclined sides 81 and 82 of which form a chute for the falling articles.

A new charge of unplated articles may 45 then be placed in the barrel after which the cover will be replaced and locked in position. If desired, while the barrel is in dumping and recharging position the plating tank may be readily cleaned out, or suitable materials added thereto to strengthen 50 the plating solution.

To return the barrel to the plating position shown in Fig. 1, the handwheel 93 will then be rotated in counter-clockwise direction. At the lowermost, or plating position 55 of the barrel, the arm 34 will engage the adjustable stop 97 and the shaft 29 of the barrel will come to rest above the recesses 28 in the tank heads 13 and 14.

As will be evident, with the present invention, the gear 88 on the shaft 29 will 60 automatically engage with the driving gear 87 without the necessity of employing a separate clutch as has been usual in the past with rotary plating apparatus. The shaft 29 will also automatically come into elec-

trical contact with the brushes 66 and the current will be turned on without requiring the use of separate switches for this purpose.

During plating, the solution in the tank 70 will be kept continuously agitated by the rotation of the barrel. The mass of small articles being plated will tumble over one another and any hydrogen bubbles which may be liberated by electrolysis on the surface of the work will thus be readily loosened therefrom and will rise to the surface of the liquid, permitting the plating to 75 efficiently proceed with great rapidity even at quite high current densities.

The flow of current through the apparatus is from the incoming lead wires 26 to the anodes 24, through the plating solution, cathode wires 61, flanges 63, shaft 29, brushes 66, and lead wires 72^a.

80 While the apparatus herein described is especially designed for the plating of metal, it will be understood that it may be employed equally well for the electrolytic cleaning of metals or other materials for 90 the removal of scale, rust, sand, etc., and also for oxidizing metals such as brass.

One advantage of the present invention 95 is that the cathode connections may be readily renewed whenever desired.

Another important advantage is that the 100 operating gears for tumbling the barrel are located entirely outside of the tank, and are arranged in such a position that lubricating oil from the bearings thereof cannot possibly drop into the plating solution.

While there has been disclosed in this 105 specification one form in which the invention may be embodied, it is to be understood that this form is shown for the purpose of illustration only, and that the invention is not to be limited to the specific disclosure, but may be modified and embodied in various other forms without departing from its spirit. In short, the invention includes all the modifications and 110 embodiments coming within the scope of the following claims.

Having thus fully described the invention, what is claimed as new, and for which it is 115 desired to secure Letters Patent, is:

1. In an electroplating apparatus, a plating tank adapted to contain a plating solution, a rotary plating barrel adapted to contain a mass of small articles to be plated, said barrel being mounted on a shaft, an arm pivoted to said shaft, said arm being pivoted on said tank, and means for rocking said arm about its axis to raise the plating barrel 120 out of the plating tank.

2. In an electroplating apparatus, a tank 125 adapted to contain a plating solution, a fulcrum shaft mounted to rotate in stationary bearings on said tank, said shaft having a lever secured thereto, a plating barrel con-

nected to the free end of said lever, a gear connected to said barrel, a driving gear mounted on said tank and adapted to mesh with said barrel gear when the plating barrel is lowered into the plating tank, a worm gear on said fulcrum shaft, a worm engaging said worm gear, and means for rotating said worm for causing said lever to rock about its fulcrum to raise and lower the plating barrel, the friction between said worm and worm gear serving to lock the plating barrel in any desired position.

3. In an electroplating apparatus, a plating tank adapted to contain a plating solution, a fulcrum shaft mounted in stationary bearings upon said tank, a lever secured to said fulcrum shaft, said lever having a rotary plating barrel secured on one end, and having a counterweight upon its other end, 20 hand-operated means for rotating said lever to raise and lower the plating barrel out of the plating tank, means adapted to tumble said barrel and operative only when it is in its lowermost position in the tank, said tank 25 having an anode and a cathode, and a resilient contact brush on said tank adapted to be electrically connected with said cathode only when the barrel is in plating position.

4. In an electroplating apparatus, a plating tank adapted to contain a plating solution, an anode and a cathode, a fulcrum shaft mounted in stationary bearings on said tank, a lever secured to said fulcrum shaft, said lever carrying a counterweight, 35 a rotary plating barrel rigidly mounted on a driving shaft, and an arm directly connecting said driving shaft and said fulcrum shaft.

5. In an electroplating apparatus, a plating tank adapted to contain a plating solution, an anode and a cathode, a fulcrum shaft mounted in stationary bearings on said tank, a lever secured to said fulcrum shaft, a counter weight on said lever, a rotary plating barrel, an arm connecting said fulcrum shaft and plating barrel, a pan secured to said fulcrum shaft to direct the plating liquid draining from the plating material back into the tank in draining position, and 50 to serve as a chute to direct the plated articles into a receptacle in dumping position, and means for manually rotating said fulcrum shaft to cause the lever and arm to rotate thereon, whereby the barrel will be 55 lifted out of the tank and swung into draining and dumping positions.

6. In an electroplating apparatus, a plating tank, a fulcrum shaft mounted on said tank, a rotary plating barrel, a frame pivoted to said barrel for swinging said barrel about said fulcrum shaft into draining and dumping positions, a driving gear, a driven gear connected with said barrel, said gears being adapted to mesh only when the barrel is in

plating position, and means for conducting 65 a current through said plating apparatus, the circuit being automatically broken when the barrel is lifted out of the tank.

7. In an electroplating apparatus, a plating tank adapted to contain a plating solution, a rotary plating barrel pivoted on a rocking frame and adapted to contain a mass of small articles to be plated, said frame being pivoted on said tank, means for 70 rocking said frame about its pivot to swing 75 the plating barrel out of the tank, means for tumbling said barrel, means for passing a current through said plating solution, said barrel-tumbling means being disengaged and said current being interrupted when the barrel is raised out of the plating solution.

8. In an electroplating apparatus, a plating tank containing a plating solution, a rocking frame pivoted on said tank, a plating barrel pivoted in the outer end of said frame, a worm and gear mechanism for rocking said frame about its pivot, and a counterweight mounted on said frame to balance the weight of said plating barrel 80 and contents, means for tumbling said barrel 90 operative only when the barrel is within the plating solution, said barrel-tumbling means being automatically disconnected when the barrel is raised out of the tank.

9. In an electroplating apparatus, a source 95 of plating current, a plating tank, an anode in said tank, a rotary plating barrel adapted to be lowered into and raised out of said tank, said plating barrel containing a cathode, a resilient metal brush secured to said tank and adapted to conduct current from said cathode when the barrel is in plating position, means for tumbling said barrel, said tumbling means being automatically 100 disengaged when the barrel is raised out of the tank.

10. In an electroplating apparatus, a plating tank containing an anode and adapted to hold a plating solution, a rotary plating barrel adapted to contain a mass of small articles to be plated, means for raising said plating barrel out of said plating solution, said plating barrel being mounted on a metallic shaft, a pair of flanges on said shaft, 110 a cathode within said barrel, means for connecting said flanges to said cathode, and a resilient brush mounted on said tank for conducting the current from said shaft during the plating operation.

11. In an electroplating apparatus, a plating tank adapted to contain an anode and a plating solution, a rotary plating barrel adapted to contain a mass of articles to be plated, a cathode in said barrel, a shaft for said barrel electrically connected with said cathode, a resilient brush on said plating tank adapted to contact with said metal shaft 125 when the barrel is in plating position, the

electrical connection between said brush and shaft being automatically broken when the barrel is raised.

12. In an electroplating apparatus, a plating tank adapted to contain an anode and a plating solution, a plating barrel adapted to rotate in said tank, said barrel being perforated to permit free circulation of the plating solution therethrough, a cathode in said barrel, said cathode comprising a plurality of spaced wires extending through both heads of the barrel and having their ends bent inwardly toward the axis of the barrel, means for electrically connecting said wires together, and means for automatically breaking the circuit through the apparatus when the barrel is raised from the tank.

13. In an electroplating apparatus, a plating tank, an anode in said tank, a plating barrel adapted to rotate in said tank, and adapted to contain a mass of small articles to be plated, a plurality of cathode elements in said barrel, said barrel being mounted on a central shaft, a pair of flanges secured to said shaft beyond the heads of said barrel, said cathode elements connected to said flanges, and means for insulating said cathode elements from the plating solution.

14. In an electroplating apparatus, a plating tank, a barrel adapted to rotate in said tank and adapted to contain a mass of small articles to be plated, a plurality of cathode elements in said barrel, said barrel being mounted on a central shaft, a pair of flanges secured to said shaft beyond the heads of said barrel, said cathode elements being connected to said flanges, each cathode element having an insulating coating except on the inside of said barrel heads.

15. In an electroplating apparatus, a plating tank, said plating tank being adapted to contain a plating solution and a cathode, and a series of substantially semi-circular anodes supported by means located below the surface of the plating solution, said anodes being electrically connected together, said anodes being adapted to be connected to the source of current at either end, and extending around the barrel under the surface of the solution.

16. In an electroplating apparatus, a plating tank, a plating barrel, an anode mounted in said tank and uniformly spaced from said barrel, said anode having a recess in one terminal, a conducting wire mounted in said recess, said wire being secured in said recess by having the edges of said recess swaged inwardly against the surface of said wire.

17. In an electroplating apparatus, a plating tank, a plating barrel, a semi-circular anode supported by insulating means located below the surface of the liquid in said tank

and uniformly spaced from said barrel, each terminal of said anode having a recess, and conducting wires swaged into each of said recesses, said anode being connected at both ends to the source of current.

18. In an electroplating apparatus, a plating tank, a series of anodes supported by insulating means in slightly raised position upon the bottom of said tank, conducting wires secured to each terminal of each anode, said conducting wires being connected to a common source of power.

19. In an electroplating apparatus, a plating tank, a barrel adapted to rotate in said tank, means for raising said barrel above said tank to draining position, means for swinging said barrel to one side of said tank to dumping and charging position, and unitary means connected with said barrel swinging means for directing the draining liquid back into the plating tank, and for guiding the plated articles while being dumped into a suitable receptacle.

20. In an electroplating apparatus, a plating tank, a frame mounted to rotate in fixed bearings upon said plating tank, a rotary plating barrel pivoted in said frame and manually operated means for rocking said frame to swing the plating barrel into plating position, draining position, and dumping position.

21. In an electroplating apparatus, a plating tank, a barrel adapted to rotate in said tank, a shaft mounted in stationary bearings at one side of said tank, means secured to said shaft for swinging said barrel out of said plating tank successively into draining and dumping positions, and a guiding pan for directing the draining liquid back into said tank and for guiding the plated work, while being dumped, into a suitable receptacle, said guiding pan having a flat bottom section, and converging side flanges, said guiding pan being secured to said shaft and rotatable therewith.

22. A tumbling barrel for an electroplating apparatus comprising a pair of heads, a series of perforated strips connecting said heads, said strips covering all but a small portion of the periphery of said barrel, the remaining portion being left open to permit the barrel to be charged and dumped, a cover for said open portion comprising a pair of segmental heads connected by a plurality of strips, said barrel heads and segmental heads having alined apertures, tubular bushings seated in said apertures, and a pair of detachable pins adapted to fit within said alined bushings to hold the cover in closed position.

In testimony whereof, I have affixed my signature to this specification.

FORREST G. PURINTON.
